UNITED STATES PATENT OFFICE.

HENRY S. BREWINGTON, OF BALTIMORE, MARYLAND, ASSIGNOR OF ONE-HALF TO WILLIAM SEIM, OF BALTIMORE, MARYLAND.

BOTTLE-WASHER MACHINERY.

SPECIFICATION forming part of Letters Patent No. 697,797, dated April 15, 1902.

Application filed September 10, 1901. Serial No. 74,985. (No model.)

To all whom it may concern:

Be it known that I, HENRY S. BREWINGTON, a citizen of the United States, residing at Baltimore city, in the State of Maryland, have 5 invented new and useful Improvements in Bottle-Washer Machinery, of which the following is a specification.

My invention relates to bottle-washers adapted for washing bottles externally; and 10 its object is to provide an apparatus of this character which will be simple and inexpensive in construction and effective and reliable in operation.

The invention comprises rotary spindles to 15 which are secured brushes and means for supplying water to the outside of the bottles.

The construction of the machine will be 20 fully described hereinafter in connection with the accompanying drawings, which form part 20 of this specification, and its novel features will be defined in the appended claims.

In the drawings, Figure 1 is a view, partly 25 in vertical section and partly in elevation, of a machine embodying the invention. Fig. 2 is a horizontal section showing a bottom plan 30 of the gearing for revolving the spindles. Fig. 3 is a vertical section, on an enlarged scale, of one of the rotary spindles and the parts attached thereto; and Fig. 4 is a plan view, partly in horizontal section, of the brushes.

The reference-numerals 1 and 2 designate 35 parallel side plates constituting the frame of the machine and provided at their lower ends with feet 3. Between the side plates is se- 40 cured a water-box 4, divided by a horizontal partition 5 into two independent chambers 6 and 7, serving, respectively, as inlet and outlet chambers for water, the chamber 6 being connected by a pipe 8 with a hydrant or other 45 source of supply, while the upper chamber 7 is provided with a discharge-opening 9.

The side plates 1 and 2 are formed with 50 bearings for a plurality of horizontal shafts 10, connected together at one end by spur- 55 gearing 11. Upon the shafts 10 are mounted bevel-gears 12, meshing with bevel-gears 13 on the lower ends of hollow rotary spindles 14. Upon the spindles 14 are also mounted 60 spur gear-wheels 15, which mesh with similar 65 gears 16, mounted upon the next adjacent

spindle 17. The spindles are thus geared together in pairs, the gear connections causing the members of each pair to revolve in opposite directions. The spindles extend through stuffing-boxes 18, and upon the upper end of 55 each spindle is secured a brush-holder comprising a disk 19 and two upwardly-projecting arms 20. The inner surface of each of the arms is formed with a longitudinal dovetail groove 21, adapted to receive a suitable 60 brush 22. The disk 19 is formed with an annular water-chamber 23, communicating by openings 24 with the spindle, and projecting upward from each of said disks are oppositely-disposed perforated pipes 25, the lower ends 65 of which communicate with the annular water-chamber 23. The pipes are in parallel relation to the brushes and are adapted to spray water onto the outside of the bottles in advance of the brushes. 70

Within each of the rotary spindles is a solid 75 rod 26, the lower end of which is suitably supported, while its upper end is formed with a circular socket 27 to receive a stud 28, depending from a rubber disk 29, serving as a 80 support for the bottom of the bottle. The upper ends of the bottles are held by spring-clasps 30 and rubber cones 31, depending from a plate 32, supported upon parallel posts 33, secured to the side plates of the machine and 85 held in position by spring-catches 34, projecting from the posts.

The operation of the mechanism will be 90 readily understood and may be described as follows: All of the shafts 10 are simultaneously revolved by means of a driving-pulley 35 on one of said shafts, and the spindles are revolved through the bevel-gears 12 and 13 and the spur-wheels 15. Water enters the hollow spindles through the perforations 36 95 and passes up to the annular chambers 23 and thence to the perforated pipes 25, which spray the water upon the bottles in front of the brushes.

The arrangement of the brush-holders in 100 oppositely-revolving pairs permits the spindles to be placed close together without danger of adjacent brush-holders striking each other.

The devices for supporting the bottles are 100

simple and secure, and the brushes may be readily removed and renewed when worn.

I claim—

1. In a bottle-washer, the combination with a water-box, and a hollow rotary spindle, of a brush-holder having upwardly-extending arms, brushes removably secured to said arms, and perforated pipes arranged adjacent to said brushes and communicating with the hollow spindle.
2. In a bottle-washer, the combination with a water-box, of a plurality of hollow spindles revolvably supported by said water-box, brush-holders carried by said spindles, and each comprising a disk having an annular water-chamber communicating with the spindle, upwardly-projecting arms to support the brushes and perforated pipes communicating with the water-chamber of the disk.
3. In a bottle-washer, the combination with a water-box and hollow rotary spindles supported thereby, of gearing connecting said spindles in pairs and causing the members of each pair to revolve in opposite directions, and brush-holders carried by said spindles.

4. In a bottle-washer, the combination with a water-box and hollow rotary spindles supported thereby, of brush-holders supported upon the spindles, brushes removably secured thereto, and yielding devices for supporting the bottles upon the brush-holders.

5. In a bottle-washer, the combination with a water-box, of hollow spindles revolvably supported thereby, brush-holders carried by said spindles, each comprising a disk having an annular water-chamber, parallel arms, and perforated pipes communicating with the spindles, and bottle-supporting devices consisting of a rod extending through the spindle, a yielding disk loosely supported on the upper end of said rod, and a plate supported above the spindles, and provided with depending clamping-springs.

In testimony whereof I affix my signature in presence of two witnesses.

HENRY S. BREWINGTON.
